UNITED STATES PATENT OFFICE.

ROBERT S. CRAWFORD, OF HAGERSTOWN, MARYLAND.

DESIGN FOR A METAL TUBE.

SPECIFICATION forming part of Design No. 24,114, dated March 12, 1895.

Application filed December 15, 1894. Serial No. 531,979. Term of patent 7 years.

To all whom it may concern:

Be it known that I, ROBERT S. CRAWFORD, a citizen of the United States, residing at Hagerstown, in the county of Washington and State of Maryland, have invented and produced a new and original Design for Metal Tubes, of which the following is a specification, reference being had therein to the accompanying drawings.

10 The leading feature of my design consists in a metal tube of unequal diameters and of a peculiar configuration. In cross section the part of said tube which may be called the top is curved upon a circle of relatively small radius, 15 while the sides thereof, below the top and running downward, curve outward to a point at or near the vertical middle portion thereof, and then slightly inward, the curves of the side portions being thus on a circle of greater radius than the curved portion of the top of the tube. The bottom of the tube is also slightly curved and the corners, where the bottom joins the sides, are slightly rounded. The longitudinal sides of the tube are parallel to 25 the longitudinal axis thereof, or approximately so.

In the accompanying drawings Figure 1 is a side view of a portion of my newly designed metal tube, and Fig. 2 is a cross section there-

of. Fig. 3 is a longitudinal section on line 30 3—3, and Fig. 4 a longitudinal section on line 4—4, of Fig. 2.

Referring more particularly to the cross-section of my newly designed tube, A denotes the curved top portion thereof and, running downward from said top portion, the sides B curve outwardly to a point slightly below the vertical middle portion of the tube, and then slightly inward, joining the curved bottom portion C of the tube on lines which are 40 curved, forming slightly rounded lower corners. The curved bottom of the tube is on the arc of a circle of much greater radius than the curved top portion thereof. The longitudinal sides of the tube are parallel to each 45 other, or approximately so, as indicated by the drawings.

I claim—

The design for a metal tube having substantially the configuration herein shown and 50 described.

In testimony whereof I affix my signature in presence of two witnesses.

ROBERT S. CRAWFORD.
